(57) **CLAIM**

The ornamental design for a plastic container, as shown and described.

DESCRIPTION

FIG. 1 is a perspective view of an embodiment of a plastic container, in accordance with the present invention;

FIG. 2 is a front view of the plastic container of FIG. 1, in accordance with the present invention;

FIG. 3 is a bottom view of the plastic container of FIGS. 1 and 2; in accordance with the present invention;

FIG. 4 is a rear view of the plastic container of FIGS. 1-3; in accordance with the present invention;

FIG. 5 is a top view of the plastic container of FIGS. 1-4; in accordance with the present invention;

FIG. 6 is a left side view of the plastic container of FIGS. 1-5; in accordance with the present invention;

FIG. 7 is a right side view of the plastic container of FIGS. 1-6; in accordance with the present invention;

FIG. 8 is a perspective view of another embodiment of a plastic container, in accordance with the present invention;

FIG. 9 is a front view of the plastic container of FIG. 8, in accordance with the present invention;

FIG. 10 is a bottom view of the plastic container of FIGS. 8 and 9, in accordance with the present invention;

FIG. 11 is a rear view of the plastic container of FIGS. 8-10, in accordance with the present invention;

FIG. 12 is a top view of the plastic container of FIGS. 8-11, in accordance with the present invention;

FIG. 13 is a left side view of the plastic container of FIGS. 8-12, in accordance with the present invention; and,

FIG. 14 is a right side view of the plastic container of FIGS. 8-13, in accordance with the present invention.

The broken lines show portions of the plastic container that form no part of the claimed design.

1 Claim, 8 Drawing Sheets
